WELL GUN

Fritz King, Sour Lake, Tex.

Application March 4, 1937, Serial No. 129,087

7 Claims. (Cl. 164—0.5)

This invention relates to a gun for use in gas, oil and water wells for the purpose of perforating screens and/or casings and for breaking up the formation adjacent thereto.

5 An object of the invention is to provide a gun made up of one or more sections containing superposed chambers each adapted to hold an explosive adapted to be discharged after the gun has been positioned properly in the well whereby projectiles will be forced through the screens or casings and into the formation.

A further object is to provide a firing element adapted to be dropped into the gun for the purpose of exploding the charges, it being possible 15 subsequently to withdraw the gun and the firing tube from the well.

A further object is to so construct the gun and firing tube as to permit the well to be washed or otherwise treated subsequently to the firing operation and prior to withdrawal of the gun.

20 With the foregoing and other objects in view which will appear as the description proceeds, the invention consists of certain novel details of construction and combinations of parts hereinafter 25 more fully described and pointed out in the claims, it being understood that changes may be made in the construction and arrangement of parts without departing from the spirit of the invention as claimed.

30 In the accompanying drawings the preferred form of the invention has been shown.

In said drawings

Figure 1 is an elevation of the gun.

Figure 2 is a vertical longitudinal section 35 through a portion thereof prior to the discharge of the explosive, a portion of the firing tube being shown in position above the explosive.

Figure 3 is a view similar to Figure 2 and showing the firing tube in its lowermost position 40 following the explosion of the charges.

Figure 4 is an elevation of a gun made up of connected sections.

Figure 5 is an enlarged section through a portion of the sectional gun, said section being taken 45 on the line 5—5, Figure 4.

Figure 6 is a longitudinal section through the firing tube.

Figure 7 is an enlarged section on line 7—7, Figure 3.

50 Figure 8 is a section on line 8—8, Figure 3. Referring to the figures by characters of reference 1 designates the tubular barrel of the gun which can be of any desired length and diameter. The wall of this gun is of sufficient 55 thickness to permit the formation therein of

sockets 2 the walls of which are screw-threaded while the inner ends of the sockets are provided with openings 3 in communication with the bore of the barrel 1. Each socket is adapted to receive a screw plug 4 having a longitudinal bore 5 the inner end of which is counterbored as at 6 and adapted to bear against the inner end of the socket 2 in which it is seated. Each bore 5 is of such diameter as to receive snugly a shell S containing an explosive and a projectile P. 10 The cap C of each shell is adapted to be seated in the counterbore 6 where it can be engaged by a firing pin 7 having a collar 8 for preventing its withdrawal inwardly from the opening 3 in which it is slidably mounted. Normally the inner 15 ends of the firing pin project slightly into the bore 9 in the barrel 1.

The sockets 2 are arranged preferably in pairs, the sockets of each pair being diametrically opposed. Any desired number of these sockets can 20 be used and each of them will of course be equipped with a plug 4 for holding a shell S.

The lower end of the barrel 1 has a screw-threaded socket 10 concentric therewith for receiving the reduced threaded end 11 of a tapered tip 12. In this tip is a longitudinal bore 13 of 25 substantially the same diameter as the bore 9 but having its upper end flared, as indicated at 14. The lower end of the bore 13 is reduced in diameter to provide a tapered seat 15.

30 Slidably mounted in the wall of the tip 12 are oppositely disposed slideable dogs 16 each of which is limited in its movement by a pin 17 projecting transversely through a groove 18 in the dog. The inner ends of these dogs are held normally projected into the bore 13 by springs 19 exerting a constant thrust against them. These springs are held under restraint by removable screw plugs 20. The inner ends of the dogs are preferably beveled as shown so that when a downwardly moving object presses against the beveled faces of the dogs, 40 said dogs will be pressed apart against the action of their springs.

The upper end of the bore 9 is preferably flared as shown at 21. It opens into the lower end of a 45 tube 22 screwed onto or otherwise attached to the upper end of the barrel 1. This tube can be of any desired length to facilitate insertion of the barrel into the well. Also, as shown in Figures 4 and 5, one or more tubes corresponding to tube 50 22 can be employed for holding together at properly spaced intervals, two or more gun barrels. In these figures the connecting tubes have been indicated at 23 while the barrels joined thereby have been indicated at 24. The construction of 55

the barrels is the same as that heretofore described, each barrel having the pairs of sockets 2 for receiving the plugs 4 which, in turn, receive the loaded shells S so as to hold them in position for engagement by the firing pins 7.

There is provided in connection with the gun, a firing tube indicated at 25, this can be of any desired length and is provided at its lower end with a tapered head or wedging element 26. The 10 diameter of this wedging element or head is slightly less than the diameter of the bore 9. The upper end of the firing tube is connected to a tubular coupling 27 having vents 28 and this coupling is designed to connect the tube to a rod 15 29 or the like of any suitable length whereby the tube can be dropped into and removed from the gun at the proper times.

In practice the gun barrel 1 is loaded with shells S containing explosives and projectiles, 20 these being placed in the plugs 4 after which the plugs are screwed into the sockets 2 provided for them. With the shells thus positioned, the firing pins will all project inwardly into the bore 9. If only one of these barrels is used, it is connected to a tube 22 sufficiently long to permit it to be lowered to the desired level. If two or more gun barrels are employed, they are connected together by the coupling tubes 23 so as to be held apart the required distances after 30 which the completed sectional gun is lowered into the well. Following the placing of the gun, the firing tube 25 is inserted into the upper end thereof and then permitted to fall. As it drops within the bores 9 of the gun barrels it wedges 35 between the firing pins and thrusts them outwardly so that the several shells are thus exploded and the projectiles propelled outwardly radially against the screen, casing and formation in the path thereof. When the firing tube reaches its 40 lowermost position it will engage the seat 15 as shown in Figure 3 at which time the dogs 16 which have been pressed laterally by the advancing head or wedge portion 26, will spring back of said portion so as to lock the firing tube within the 45 gun. Consequently pressure of gases or the like will not operate to force the tube upwardly but can escape through the tube and out by way of the vents 28 and the coupling 27. Furthermore while the tube is still in position, the well can 50 be washed or otherwise treated through this firing tube.

Following the treatment of the well as described, the entire structure can be removed readily therefrom, reloaded and again used as 55 explained.

What is claimed is:

1. A gun of the class described including a barrel having opposed sockets in the wall thereof, means in each socket for holding an explosive 60 shell, a firing pin normally projecting into the bore of the barrel and positioned for engagement with the cap of the shell, and a firing element mounted to gravitate longitudinally within the barrel for engaging the pins to shift them and 65 explode the caps of the shells.

2. A gun of the class described including a barrel having a bore, sockets opening outwardly within the wall of the barrel and inwardly into the bore, firing pins within the inner portions of 70 the sockets and normally projecting into the bore, means removably seated in the sockets for holding an explosive shell in each socket with the cap thereof in position for firing by the pin, and a firing element mounted to gravitate longitudi-

nally of the bore for engaging and actuating the firing pin.

3. A gun of the class described including a barrel having a bore, sockets opening outwardly within the wall of the barrel and inwardly into the bore, firing pins within the inner portions of the sockets and normally projecting into the bore, means removably seated in the sockets for holding an explosive shell in each socket with the cap thereof in position for firing by the pin, a 10 firing element mounted to gravitate longitudinally of the bore for engaging and actuating the firing pin, and means for automatically locking said firing element against return movement within the bore. 15

4. A gun of the class described including a barrel having a bore, sockets opening outwardly into the bore, firing pins within the inner portions of the sockets and normally projecting into the bore, means removably seated in the sockets for holding an explosive shell in each socket with the cap thereof in position for firing by the pin, a 20 firing element slideable longitudinally of the bore for engaging and actuating the firing pins, and means for automatically locking said firing element against return movement within the bore, said element being tubular and provided with a 25 vent.

5. A gun of the class described including a barrel having a bore, there being opposed sockets 30 in the wall of the barrel, means removably seated in the sockets for holding explosive shells therein, firing pins extending into the sockets and normally projecting into the bore, a firing tube slideable longitudinally of the bore for actuating 35 the firing pin, said tube having a wedging portion at its advancing end for engagement with the firing pin, means for limiting the movement of the firing tube in one direction, and means for automatically locking said tube against movement in the opposite direction.

6. A gun of the class described including an elongated barrel having a bore, there being a plurality of opposed sockets in the wall of the barrel, means removably mounted in each socket for 45 holding an explosive shell having a cap and a projectile, firing pins projecting from the sockets into the bore and positioned for exploding the cap, a firing tube having a wedge portion at its advancing end and adapted to move longitudinally of the bore to engage and deflect the firing pins thereby to explode the caps, a seat for limiting the advancing movement of the firing tube, there being a vent in said tube, and means for locking the tube against movement away from the 50 barrel. 55

7. A gun of the class described including an elongated barrel having a bore, there being a plurality of opposed sockets in the wall of the barrel, firing pins extending into the sockets from within the bore, means removably seated in the sockets for holding explosive shells positioned to be fired by the pins, a tip removably attached to one end of the barrel and having a seat, there being a bore extending through the tip, opposed yieldingly 60 restrained dogs slideable within the tip, and a firing tube having a wedge portion, said tube being movable longitudinally within the bore to successively engage and shift the firing pins, engage and shift the dogs, and engage the seat, said dogs 65 constituting means for automatically engaging the firing tube to hold it against withdrawal from the barrel. 70
